ABSTRACT OF THE DISCLOSURE

A web tensioning device to automatically control the tension on a web as it is fed into and through a machine for processing and taken up readily adaptable for intermittent progressive step operations providing a lever, one end of which impinges upon the web, the lever in pivoting actuating web payout with the web payout controlled by a pair of switches. A first switch pays out the web by actuating the web payout rollers, the second switch deactivates the web payout rollers and substantially prevents paying out of the web. The switches are actuated by means carried on the lever which come in contact with the switches when the lever pivots, the lever pivot being dependent upon the take up and payout of the web.

The present invention relates to a web tensioning device.

In many fields, but particularly in the printing field where a web of material is required to be fed through a machine for processing proper registration is critical or substantial waste by way of misregistration may occur.

For example, many printing operations are progressive step operations such as found in label making where a web as processed is subjected to various environments during certain stages of production such as heating, embossing, printing and cutting, and in order that there be proper registration it is necessary that the web enter each of these stages under desired tension so as to maintain the web in a given spacial relationship with the various tools and dies employed.

Problems of proper registration are accentuated in cases where reciprocating printing equipment is employed since there is added to the problem of registration during a progressive step operation, the problem of the intermittent or stop and go feeding of the web through its various processing stages.

In order to overcome the foregoing problem, not only in the printing field, but in all fields where a web is being run through a machine or process and proper registration is necessary, various devices have been employed in an attempt to provide the necessary registration.

In some instances these devices took the form of regulating means which controlled the speed of the web payout and/or attempted to synchronize the web payout with the processing steps. These devices were inefficient or difficult to regulate especially in intermittent type operations because of the "stop and start" nature of the operation. In addition the web registration was attempted to be controlled by a synchronization of pay out to processing steps with little or no provision for otherwise maintaining a constant tension on the web.

Registration of a web by tensioning alone or in combination with other equipment also had many inherent difficulties. While the proper tension might be found for a particular web after determining the strength and stretch characteristics of the web, the devices employed for such tensioning were generally limited to a web of given norm characteristics and the resetting of the tension for webs of differing characteristics especially where such tensioning mechanism was interrelated to other

2

regulating systems was a somewhat complicated operation.

According to the present invention a web tensioning device is provided which provides constant tension on the web both during payout and rest and allows for a single speed payout regardless of the web and web processing equipment employed.

The web tensioning device of the present invention automatically controls the tension on the web as it is fed into and through a machine for processing and taken up and is readily adapted for intermittent progressive step operation.

The web is threaded between a pair of rollers, one of which is actuatable upon a signal to payout the web. 15 The web is then positioned so as to have the weight of a lever arm depend thereon. As the web is taken up during processing the amount of web between the processing machine and the pay-out rollers lessens, and this shortening of the web length pivots both ends of the lever about its fulcrum. At a selected point during take up the lever comes in contact with first switch means to actuate the motor which controls the payout rollers causing the payout rollers to feed web out. As the web is payed out the weight of the end of the lever arm which depends upon the web maintains the web in constant tension and pivots the lever. At a selected point during payout the lever comes in contact with second switch means which deactivates the payout rollers. The tensioned web is continually taken up and payed out as required by the processing machine.

Proper control of the payout motor switches is maintained by provision of switch actuation means on the lever at a point on the lever of a radial distance greater than the greatest distance from the fulcrum of the lever 35 to the edge of the fulcrum support in the area of the switches, and by having the actuating arms of the switches projecting beyond the edge of the fulcrum support so as to lie in an intersecting plane with the switch actuation means, the arc described by the pivoting lever bringing the switch actuation means in contact with the switch arms at selected points along such arc.

Although such novel feature of features believed to be characteristic of the invention are pointed out in the claims, the invention and the manner in which it may 45 be carried out may be further understood by reference to the description following and the accompanying drawings.

FIG. 1 is a side elevation of a device of the present invention as employed with a label making machine.

50 FIG. 2 is a side elevation of a device of the present invention.

FIG. 3 is a perspective view partly broken away of a device of the present invention.

FIG. 4 is a detailed sectional view of the payout roller 55 driver means.

Referring now to the figure in greater detail, where like reference numbers denote like parts in the various figures.

As shown in FIGS. 1-3 the tensioning apparatus 1 is 60 interposed between the web spool 2 and the working structure shown schematically as a label printing, stamping, embossing and cutting machine 3 which may run a second web 4 at right angles to the web 5 in processing, and is in the nature of the apparatus described in my U.S. Patent No. 3,289,573 dated Dec. 6, 1966.

The tensioning apparatus 1 generally comprises a frame interposed between the web spool 2 and the label machine 3, the frame preferably having spaced apart vertical side walls 6. As shown in FIGS. 1-3 and as hereinafter more fully described, the edge of the lower section 14 of 70 each of the side walls 6 facing the web spool 2 is prefer-

ably substantially vertical and the edge of the upper section 15 of each of the side walls 6 facing the web spool 2 is inclined at angle away from the web spool 2.

A drive roller 7 is rotatably mounted between the side walls 6 preferably near the upper portion of the walls 6 and a guide roller 8 is preferably rotatably mounted in parallel vertically closely spaced apart relationship to the drive roller 7 so that the web 5 threaded between the rollers 7, 8 will be impinged therebetween and substantially prevented from paying out until rotation of the rollers 7, 8. It is readily apparent that the positions of the rollers 7, 8 may be reversed so as to have the feeding, or drive roller 7 as the upper roller and the guide roller 8 as the lower roller.

A lever 9 is pivotally mounted between the side walls 6, the fulcrum 10 of the lever 9 preferably located below the rollers 7, 8. The lever 9 as shown extends through the frame defined by the walls 6 with a portion of the lever 9 between the web spool 2 and the walls 6 projecting outward from between the walls 6. Although as shown in FIGS. 1-3 both end portions of the lever 9 extend outward of the frame defined by the walls 6, if desired, the walls 6 may be of sufficient width so that the length of the lever 9 between the fulcrum 10 and the work piece 3 may be masked between the walls 6.

The lever 9 is preferably an openwork frame of two arms 11 interconnected at a point near the outer ends of the arms 11, such interconnection preferably made by a rotatably mounted guide 12.

Each arm 11 is preferably provided with a looped end portion 16 which is disposed between the fulcrum 10 and the web spool 2, each arm 11 thereby being substantially J-shaped.

In normal position, the lever 9 is balanced so that greater weight is present at the portion of the lever 9 between the fulcrum 10 and the work piece 3 the lever 9 thereby pivoting so as to be inclined with the portion of the lever 9 between the fulcrum 10 and the work piece 3 below the horizontal.

While the desired normal position of the lever 9 is inclined as aforementioned, the requisite force to be applied by such inclined lever 9 is dependant upon a combination of variant factors, such as the resiliency of the web 5 and the strength of the take-up of web 5 by the work piece 3. As shown in FIGS. 1-3 selective control of the lever 9 may be readily provided by the use of weights 17 which may be provided in various numbers or weight on both or either side of fulcrum 10. The looped end portion 16 of the lever 9 is readily amenable to accommodate weights 17 along the entire length of the shorter leg of the J leaving the lower section below the shorter leg of the J free to carry a portion of the payout controls shown as plate 18.

The plate 18 is mounted on one of the arms 11 so as to project outward transversely from the arm 11 so as to lie in an intersecting plane with the edge of the side wall 6. The plate 18 is mounted along arm 11 at a point of a greater radial distance from the fulcrum 10 than the radial distance from the point of meeting of the vertical edge and the inclined edge of the wall 6. In such manner, during the pivoting of the lever 9 the arc described by the lever 9 at the point of affixation of the plate 18 will carry the plate 18 from a point above the inclined edge to a point above or along the vertical edge.

As shown in FIGS. 2 and 4 the payout roller 7 is actuatable to rotation by a motor 19. The actuation of the motor 19 is controlled by switches 20 and 21 respectively, the switches 20, 21 in the nature of microswitches having spring contacts 22.

The switches 20, 21 are disposed along the side wall 6, with the contact 22 of switch 20 projecting above the inclined edge of wall 6 and the contact 22 of switch 21 projecting beyond the vertical edge of wall 6, both contacts lying in a plane which will intersect plate 18 upon pivoting of the lever 9.

Upon actuation, by plate 18 causing contact 22 of switch 21 to make contact, motor 19 is actuated and payout roller 7 is actuated to feed out web 5. When plate 18 actuates switch 20 by causing the contact 22 of switch 20 to make contact, the motor 19 is deactivated and the circuit of switch 21 is broken thereby stopping further payout of the web 5.

In operation, the web 5 taken from web spool 2 is threaded between rollers 7, 8, threaded under guide 12 and thence to the work piece 3 to the take-up roller 23. The web 5 is maintained tensioned by the guide 12 bearing downward upon the web 5. As the web 5 is taken up, the take-up pull of the web will cause the lever 9 to pivot upward. The plate 18 will pivot downward until plate 18 actuates switch 21. Upon actuation of switch 21 web 5 will be payed out by rollers 7, 8 thereby causing the guide 12 end of the lever 9 to pivot downward. This will bring plate 18 into contact with switch 20 which will deactivate the motor 19, the switch 20 causing payout to cease.

The payout of the web 5 through rollers 7, 8 when actuated is selectively timed so as to be at least equal to, and preferably slightly greater than the speed of the take-up 23. In this manner the web 5 is constantly tensioned by the weight of the guide 12 end of the lever 9.

While the fulcrum 10 has been illustrated as being interposed between the web spool 2 and the rollers 7, 8 it is readily apparent that the rollers 7, 8 may be mounted separately at a point between the web spool 2 and the fulcrum 10 and the supporting structure for the fulcrum 10 a simple arrangement of two vertical supports. Any such arrangements or modifications provides for a constant tensioning of a web by a lever arm during the reciprocating of the lever, with the reciprocating of the lever a payout control for the web.

It is to be further understood that the payout speed need only be sufficient to be equal to or to exceed the speed of take-up of the web processing machine. In this manner no sophisticated synchronization equipment for the synchronization of the payout speed to take up speed need be employed, however if desired the motor 19 may be of the type which has various speed settings and in this manner the tensioning device of the present invention may be employed interchangeably with various web processing equipment having differing take-up speeds, and as shown in FIG. 1 the web tensioning device may be portable and mounted on a wheeled platform 24.

The terms and expressions which are employed are used as terms of description; it is recognized, though that various modifications are possible.

Having thus described certain forms of the invention in some detail, what is claimed is:

1. A web tensioning device comprising, a lever mounted between a web source and web take up means, said lever including a lever support, a portion of said lever adapted to impinge upon said web to tension said web, web payout means adapted to deactivate the feeding out of said web, said web payout means including power means; first switch means adapted to actuate said power means to feed out said web and second switch means adapted to deactivate the feeding out of said web, said first and second switch means mounted on said support with the contacts of said first and second switches at points substantially along a portion of such support, switch actuation means on said lever adapted to actuate said first and second switch means upon pivoting of said lever, the taking up of said web pivoting said lever to bring said switch actuation means into contact with said first switch means and the feeding out of said web pivoting said lever to bring said switch actuation means into contact with said second switch means, said switch actuation means mounted at a point on said lever of a radial distance greater than the greatest distance from the fulcrum of said lever to the edge of said support in the area of said switches.

2. The apparatus of claim 1 wherein said web payout

means further includes a pair of rollers adapted to impinge a web therebetween, said web fed out upon rotation of said rollers.

3. The apparatus of claim 1 wherein said lever comprises an openwork frame including guide means for said web.

4. The apparatus of claim 1 wherein said lever comprises an openwork frame, each side of said frame a substantially J-shaped member having the shorter leg of said J opposite said impinging portion of said lever and said impinging portion includes roller means interconnecting said J-shaped members.

5. The apparatus of claim 1 wherein said switch actuation means includes a substantially vertical plate mounted on said lever.

6. The apparatus of claim 1 wherein said lever further includes removably mountable weights adapted to be mounted on said lever at points along its length.

7. The apparatus of claim 1 wherein said lever support includes a pair of vertical side walls, the lower portion 20 of at least one of said side walls facing said web source

being substantially vertical, the upper portion of said last mentioned side wall facing said web source inclined away from said web source, said first switch means mounted on said lower portion of said side wall, said second switch means mounted on said upper portion of said side wall, and said contact portions of each of said first and second switches disposed beyond the edge of said side wall.

8. The apparatus of claim 7 wherein said web payout means are mounted on said lever support, said web payout means including a pair of rollers mounted between said vertical side walls at a point above said lever.
